(57) **CLAIM**

The ornamental design for a multi-surface bag design, as shown and described.

DESCRIPTION

FIG. 1 is a perspective view from the top-left of the multi-surface bag in a first state;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a perspective view from the top-left of the multi-surface bag in a second state;

FIG. 9 is a front view thereof;

FIG. 10 is a back view thereof;

FIG. 11 is a right side view thereof;

FIG. 12 is a left side view thereof;

FIG. 13 is a top view thereof; and,

FIG. 14 is a bottom view thereof.

The broken lines are for the purpose of illustrating portions of the article and form no part of the claimed design. The cross-hatching shown on FIGS. 3, 8, 9, and 10 represents a different material or treatment from the other portions of the article.
